HEATING PLANT

James F. McIntire, Detroit, Mich., assignor to
 United States Radiator Corporation, Detroit,
 Mich., a corporation of New York

Application December 12, 1938, Serial No. 245,313

2 Claims. (Cl. 126—242)

This invention relates generally to stoker-fired heating plants of the domestic type such as stoker-fired boilers, warm air furnaces and the like wherein soft coal is used as the fuel, and refers more particularly to an improved installation which includes a clinker receptacle.

Heretofore it has been customary to remove clinkers from the fuel bed within the fire box of such a heating plant by pulling them forwardly through the tending door thereof onto the floor of the boiler room. Often the clinkers removed in this manner are red hot and present a fire hazard in the boiler room and a heat loss in so far as the heating plant is concerned. Fumes are released from such clinkers into the boiler room and frequently these fumes contain sulphurous or other harmful gases. The handling of clinkers in the boiler room as described also causes dirt and dust and requires suitable storage space which from an appearance standpoint is usually objectionable. Moreover, it is impracticable to wet down clinkers on the floor of the boiler room as such procedure not only results in a messy floor but causes the formation of too much steam which is destructive to the furnishings of the home or building in which the heating plant is installed.

To avoid and overcome the objections to and disadvantages of the conventional type of domestic heating plant, I have provided an improved installation which includes a clinker receptacle that is so constructed and arranged relative to the fire box of the heating plant that clinkers may be moved from the fire bed to such receptacle and stored therein without the fire hazard, loss of heat, dirt, dust, etc., mentioned above. Moreover, my structure is such that the operator may wet down the clinkers in the receptacle if he desires to do so without the resulting steam damaging any of the furnishings.

In the accompanying drawings:

Figure 1 is a side elevation, with parts broken away and in section, of a boiler-stoker installation embodying my invention;

Figure 2 is a sectional view taken substantially on the line 2—2 of Figure 1;

Figure 3 is a view similar to Figure 1 but showing a modification;

Figure 4 is a rear elevation of the structure illustrated in Figure 3;

Figure 5 is a detail perspective view of the clinker receptacle illustrated in Figures 3 and 4;

Figure 6 is a view similar to Figure 1 but showing another modification.

Referring now to the drawings, A is the boiler,

and B is the stoker of an installation embodying my invention.

In the present instance, the outlet 1 of the stoker is within the fire box 2 of the boiler adjacent the tending opening 3 in the front wall 4 of the boiler, and a partition or bridge wall 5 is provided within said boiler in spaced relation to the rear wall 6 thereof to provide a storage chamber 7 for clinkers. A clean-out opening 8 is provided in the rear wall 6 of the boiler to afford access to the storage chamber 7. Doors 9 and 10 of suitable construction are provided for the openings 3 and 8, respectively.

Thus, with the construction as described the partition 5 is high enough to retain fuel on the stoker side thereof but is low enough to permit clinkers to be dropped over it into the storage chamber 7. In practice a suitable hook or poker 11 may be inserted through the tending opening 3 and moved upwardly and rearwardly from the full line to the dotted line positions illustrated in Figure 1 to transfer clinkers from the fire bed in the fire box 2 to the storage chamber 7, instead of moved forwardly to draw the clinkers through the tending opening 3 into the boiler room as heretofore. This eliminates all the objections mentioned above. In fact, the clinkers may remain in the chamber 7 until the operator is ready to have them removed from the boiler room. Moreover, they can be sprayed with water before being removed. It should also be noted that my construction is such that gases and heat from the clinkers in the storage chamber 7 pass upwardly into and are received by the combustion chamber 12 above the fire box 2 of the boiler, hence there is no heat loss or damage to furnishings.

In Figures 3, 4 and 5 I have illustrated a modification in which the clinker receptacle 20 is separate from and removably mounted upon the outside of the boiler A'. As shown, the receptacle 20 has an opening 21 registering with an opening 22 in the rear wall 23 of the boiler for receiving clinkers from the fire box 24. Preferably a lateral flange 25 projects outwardly from the edges of the opening 22 into the opening 21 of the receptacle so as to assist in supporting the latter. Retaining lugs 26 are fixed to the rear wall 23 of the boiler above the opening 22 and have inclined edges 27 for engagement with an upstanding flange 28 at the upper edge of the opening 21 in said receptacle. Thus, engagement of the upper edge of the opening 21 with the lateral flange 25 and of the flange 28 with the lugs 26 maintains the edges of said opening 21 against

the rear wall 23 of the boiler. Handles 29 and 30, respectively, are provided on top and on the rear wall of the receptacle for moving the latter into and out of engagement with the lugs 26 and 5 for carrying the receptacle while it is removed from the boiler.

In practice, a suitable hook or poker 31 may be inserted through the tending opening 32 in the front wall of the boiler and moved from full 10 line to dotted line positions illustrated in Figure 3 to transfer clinkers from the fire bed in the fire box 24 through the openings 22 and 21 into the receptacle 20. The receptacle 20 may then be tilted slightly to be removed from the boiler 15 and may then serve as a scuttle to carry the clinkers from the boiler room. Any suitable cover (not shown) or another receptacle like 20 may be used to close the opening 22 in the boiler while the first mentioned receptacle is detached.

20 Thus, the construction not only eliminates the objections mentioned above but also obviates the necessity of removing clinkers from a storage space or chamber to a portable receptacle. The receptacle 20 itself is portable yet is mounted on 25 the boiler A' in such a way that gases and heat from clinkers in the receptacle will pass through the registering openings 21 and 22 into the combustion chamber 33 of the boiler. Consequently, 30 there is no heat loss or fire hazard, etc., as herefore.

Preferably the clinker chamber 1 and the receptacle 20 are opposite the tending openings 3 and 32, respectively, but obviously such chamber and receptacle may be located elsewhere relative to such tending openings, as long as they 35 are in position to receive clinkers from the fire bed and may be reached from the tending openings by a suitable implement. It should also be noted that in Figures 1 and 2 the partition 5 extends to the bottom 13 of the boiler and that in Figure 3 the receptacle 20 is mounted opposite and in substantially a horizontal plane with the fire box 24 of the boiler, hence in each instance the clinkers are received in chambers or 40 receptacles separate from and independent of the stoker spaces 14 and 34, respectively, of the boilers. Any suitable means (not shown) may be employed as outlets for ashes from such boilers.

50 In Figure 6 I have shown another modification wherein the partition or bridge wall 40 is adjacent the front wall 41 of the boiler, while the outlet 42 for the stoker 43 is substantially midway between said partition 40 and the rear wall 44 of the boiler. In this construction the 55 stoker 43 extends through a suitable opening in a side wall of the boiler, and the clinkers are

adapted to be removed from the clinker chamber 45 through opening 46 in the front wall 41 of the boiler. Any suitable door such as 47 may be used to normally close the opening 46. Thus, with the construction just described, the partition 40 is high enough to retain fuel on the stoker side thereof but is low enough to permit clinkers to be dropped over it into the storage space or chamber 45. In practice a suitable hook or poker such as 48 may be inserted through 10 the tending opening 49 in the front wall of the boiler and moved upwardly and forwardly from the full line to the dotted line positions illustrated in Figure 6 to transfer clinkers from the fire bed in the fire box 50 to the storage chamber 45. Thus, only one door such as 47 is required at the bottom of the boiler.

What I claim as my invention is:

1. A heating plant having a fire box and a combustion chamber arranged in superposed relation and an outer casing for said fire box and combustion chamber, one upright wall of said casing being provided adjacent the upper end of the fire box with a clinker opening, another upright wall of said casing being provided adjacent 25 the lower end of the combustion chamber with a tending opening through which a suitable tool may be inserted to move clinkers from the fire box through the clinker opening, the upright walls aforesaid being in opposed substantially 30 parallel relation to each other, the openings in said opposed upright walls being substantially in horizontal alignment, and a removable clinker receptacle mounted upon the outside of the first mentioned wall for receiving and containing 35 clinkers discharged through said clinker opening.

2. A heating plant having a combustion chamber, a fire box below and opening upwardly into said combustion chamber, and an outer casing 40 for said fire box and combustion chamber, the rear upright wall of said casing being provided adjacent the upper end of the fire box with a clinker opening, the front upright wall of said casing being provided adjacent the lower end of 45 the combustion chamber with a tending opening through which a suitable tool may be inserted to move clinkers from the fire box through the clinker opening, a clinker receptacle upon the outside of the first mentioned wall for receiving and containing 50 clinkers discharged through said clinker opening, and a mounting for said receptacle permitting quick separation of the receptacle from said casing and access to said clinker opening.

JAMES F. McINTIRE.
